(57) **CLAIM**

The ornamental design for a cartridge for vaporizer device, as shown and described.

DESCRIPTION

FIG. 1 is a front perspective view of a cartridge for vaporizer device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures depict portions of the cartridge for vaporizer device that form no part of the claimed design.
